(57) **CLAIM**

The ornamental design for a sitting posture warning device, as shown and described.

DESCRIPTION

FIG. 1 is a front, right and bottom perspective view of a sitting posture warning device, showing my new design; FIG. 2 is a rear, left and top perspective view thereof; FIG. 3 is a front view thereof; FIG. 4 is a rear view thereof; FIG. 5 is a left side view thereof; FIG. 6 is a right side view thereof; FIG. 7 is a top plan view thereof; and, FIG. 8 is a bottom plan view thereof. The broken lines shown in the drawings illustrate portions of the sitting posture warning device that form no part of the claimed design.
